CLAIM

The ornamental design for a motor vehicle front bumper, as shown and described.

DESCRIPTION

FIG. 1 is a top, front and left side perspective view of a motor vehicle front bumper showing our new design; FIG. 2 is a top, front and right side perspective view thereof; FIG. 3 is a front elevational view thereof; FIG. 4 is a rear elevational view thereof; FIG. 5 is an enlarged left side elevational view thereof; FIG. 6 is an enlarged right side elevational view thereof; FIG. 7 is a top plan view thereof; FIG. 8 is a bottom plan view thereof; and, FIG. 9 is another front elevational view thereof, shown mounted on a motor vehicle that is shown in broken lines for illustrative and environmental purposes that form no part of the claimed design.
